UNITED STATES PATENT OFFICE

FRANK H. HEITGER, OF FLINT, MICHIGAN

CARBURETOR

Application filed July 21, 1927. Serial No. 207,488.

This invention relates to carburetors, and more particularly to improvements in the choke valve usually provided in the carburetor air intake, and the invention has for one of its objects to provide means for automatically regulating the choke valve so as to insure a supply of uniformly rich mixture in the interval from the moment the engine is started, until it is brought up to its normal operating temperature, the automatic regulation of the valve being combined with a manually adjusting device for varying the limits of the automatic control.

A further object is the provision of an automatic regulating device employing a spring as an essential element in the regulation of the valve.

Referring to the accompanying drawings, wherein an approved embodiment of the invention is illustrated:

Fig. 1 is a side elevation of a conventional carburetor illustrating the invention applied thereto.

Fig. 2 is a section on the line 2—2 of Fig. 1.

Figures 3 and 4 are diagrammatic views showing portions of the regulating device.

Fig. 5 is a fragmentary side elevation of a carburetor, illustrating a modification of the invention, and

Fig. 6 is a similar view of a further modification.

Referring to the drawings in detail, numeral 5 indicates a conventional type of carburetor including a throttle control arm 6, fuel reservoir 7, and air intake 8 in which the shaft 9 supporting the choke valve 10 is journalled.

According to the present invention, the shaft 9 is located in a plane below the axis of the air intake 8, in order that the differential pressure active on the valve, incident to the air being drawn through the inlet, normally tends to open the valve. External-
ly of the air inlet 8, an arm 11 is secured to the supporting shaft 9, and carries at its outer end, a swivelly mounted slide collar 12 receiving the manually operable choke rod 13, which, as will be understood, is extended to a point within convenient reach of the operator of the engine.

A pair of stop collars 14 and 15 are secured in adjusted position on the rod 13 by set screws 16, and the rod is thus capable of a limited amount of longitudinal movement independently of the slide collar 12, such movement being limited according to the space between the stop collars 14 and 15.

In the position of the rod 13, as shown in Fig. 1, the collar 15 abutting the slide collar 12, positively maintains the choke valve 10 in closed position, and according to this adjustment of the device, the automatic regulation of the valve is ineffective.

An adjustable abutment 17, secured in place by a set screw 18, or equivalent device, is secured to the extremity of the rod 13, and an expansion spring 19 confined between said abutment and the slide collar 12, normally tends to so displace the arm 11 with respect to the rod 13, as to resiliently retain the valve either in closed position, or in such near closed position as the rod 13 will admit, owing to engagement of the slide collar 12 with the stop collar 14.

According to modern practice in the construction and design of carburetors, the choke valve when partially closed, so as to supply a mixture sufficiently rich in liquid fuel as to afford proper combustion of an engine during the warming up period, for a certain position of the throttle is ineffective in maintaining uniformity of the proportion of the liquid fuel at other positions of the throttle, than that for which the choke valve was originally adjusted, and hence the fuel mixture is of the improper proportion and the engine fails to fire regularly.

The present invention, however, overcomes this objection to known types of choke valves for the reason hereinafter more fully explained, and in operation, when the engine is initially started in a cold condition, the choke valve 10 is positively retained in closed position by affecting the adjustment of the rod 13 to supply an exceedingly rich mixture for initial starting purposes. Thereafter, the rod 13 is adjusted to the position shown in Fig. 3, so as to permit of a limited opening movement of the throttle 10, the extent of such opening movement being de-

terminated by the operator according to the thermal condition of the engine. Having effected such adjustment of the choke rod, the valve 10 is so regulated as to admit only the proper quantity of air according to the suction effect acting thereon. For instance, when the engine is running at relatively low speed, and the pressure difference of the valve is correspondingly low, the spring 19 5 acts against the pressure of the incoming air, moves the valve to a position farther closed, whereas when the pressure effect on the valve increases, the latter is opened against the tension of the spring to admit 10 a greater quantity of air. When the engine has been heated sufficiently for normal running, the rod 13 is manually displaced sufficiently to positively maintain the valve 10 in opened position against the stop 20. 15 According to the modification illustrated in Fig. 5, the valve 10 constructed and mounted on the shaft 9 as previously described, is mounted on the intake of the carburetor and the arm 21 thereof is connected 20 with a contractile spring, the tension of which normally acts to move the valve to closed position against the pressure effect of the incoming air. As will be understood, the extremity of the spring 22, opposite the arm 25 21, is suitably connected with a stationary part of the carburetor.

The opening movement of the valve is variably limited by a stop collar 23, adjustably mounted on the choke rod 24 which latter 30 passes through the extremity of the arm 21. A second stop collar 25, coacting with the arm 21 to positively maintain the valve in opened position, is also adjustably mounted on the rod 24.

40 The operation of this form of the invention is substantially the same as that described in connection with the form of the invention first illustrated, except that the spring normally tending to close the valve 45 instead of coacting directly between the arm and choke control rod is interposed between the carburetor body and valve arm.

The arrangement according to the modification illustrated in Fig. 6 is substantially 50 the same as that illustrated in Figs. 1 to 4, except that the arm 11, instead of being arranged to extend upwardly from the shaft 9 when the valve is closed, is so disposed as to extend downwardly from said shaft when 55 the valve is closed.

In view of the similarity of the construction and arrangement of parts, the same reference numerals have been used in Fig. 6 as those employed in Figs. 1 to 4 inclusive.

60 As proposed in another of my pending applications, the spring in either of the forms of the invention illustrated, may be constituted by thermo sensitive elements, which, when exposed to the exceedingly low 65 temperatures, increase the tension of the

spring to such extent as to offer greater resistance to the opening movement of the valve under the influence of the incoming air, than is presented under more moderate temperature conditions. The spring being 7 in a position in proximity with the engine, is affected by the heat radiated from the latter, as the engine is warmed to normal working temperature, and thus the tension 7 of the spring is gradually reduced to normal, as the engine temperature approaches a more moderate thermal condition.

What I claim and desire to secure by Letters Patent is:

1. In a carburetor, an air inlet, a choke valve in said inlet opened in response to incoming air, a manually operable choke valve rod, stop collars arranged in spaced relation on said rod, an arm on said valve movable between said stop collars, and spring means interposed between the rod and arm, normally tending to move the valve to closed position.

2. In a carburetor, an air inlet, a choke valve in said inlet opened in response to incoming air, a manually operable choke valve rod, stop collars arranged in spaced relation on said rod, an arm on said valve movable between said stop collars, spring means interposed between the rod and arm normally tending to move the valve to closed position, and means adjustably securing the stop collars on said rod.

3. In a carburetor, an air inlet, a choke valve in said inlet opened in response to incoming air, a manually operable choke valve rod, stop collars arranged in spaced relation on said rod, an arm on said valve movable between said stop collars, spring means interposed between the rod and arm normally tending to move the valve to closed position, and means for varying the tension of said spring means.

4. In a carburetor having an air inlet, a valve mounted therein so as to be operated by suction, said valve being normally out of action, except when warming up, spring means to resist the opening of the valve, and means to, at will, from a distant point, regulate said spring, and also to positively hold said valve closed, and wide open out of action.

5. In a carburetor having an air inlet, a valve mounted therein so as to be operated by suction, said valve being normally out of action, spring means to resist the opening of the valve, and means to, at will, regulate said spring, and also positively hold said valve closed, and wide open out of action.

6. In a carburetor having an air inlet, a valve mounted therein so that it may be operated by suction, said valve during normal operation of the carburetor being positively held wide open and out of action, means operable from a distant point to positively

1,881,560

close said valve for starting the motor to which the carburetor is attached and to positively open it wide, said last mentioned means being adapted to adjust a spring which comes into action when the valve is released from a positive closed position to yieldably oppose the valve opening by suction.

In testimony whereof I hereunto affix my
signature.

FRANK H. HEITGER.
